UNITED STATES PATENT OFFICE.

HAVILAND H. PLATT, OF NEW YORK, N. Y.

METHOD AND APPARATUS FOR CONVERTING MOTION.

1,414,895.

Specification of Letters Patent.

Patented May 2, 1922.

Application filed April 24, 1920. Serial No. 376,215.

To all whom it may concern:

Be it known that I, HAVILAND H. PLATT, a citizen of the United States, residing in New York city, New York, have invented 5 Methods and Apparatus for Converting Motion, of which the following is a specification.

One object of this invention is to provide a method for converting the unrestrained, 10 random, straight line motion of small bodies of metal into the useful motion of larger bodies; the invention further contemplating the provision of a device capable of illustrating by mechanical analogy, the possibility 15 of converting some of the unrestrained random motion of the molecules in the atmosphere into the motion of a machine capable of performing useful work.

These objects and other advantageous ends 20 I attain as hereinafter set forth, reference being had to the accompanying drawings, in which,

Fig. 1 is a plan of a device which may be employed for imparting random motion to 25 small bodies;

Fig. 2 is a vertical section on the line 2—2, Fig. 1; with the rotor removed;

Figs. 3 and 4 are respectively a plan and a 30 side elevation on a larger scale than that of Figs. 1 and 2, illustrating one form of rotor for use with the device of said first figures; and

Figs. 5 and 6 are respectively a plan and a 35 side elevation of a second form of rotor.

In the above drawings 1 represents a circular table mounted on a supporting structure 2 and having a flat horizontal top, at 40 whose center is fixed a vertically extending spindle or pivot 4 while around its edge are mounted a number of vibratory blocks or 45 hammers 3 preferably made of hardened steel or the like. These hammers are respectively fastened to the longer of the two arms of U-shaped springs 5 which are in turn fixed to the circular edge of the table 50 so as to project radially therefrom. A spacing block 6 is mounted between the shorter arm of each of the springs and the table to allow the former to freely vibrate and 55 each spring has fixed to its outer arm a plunger 7 extending radially inward and freely movable through an opening in its shorter arm in a line just below and parallel with the lower surface of the table.

The supporting structure 2 is provided 55 with a central journal on which is rotatably

mounted a pulley 9 connected integrally or otherwise to a cam 8 so positioned as to successively engage and force outwardly the various plungers 7 as said cam is turned. 60 The latter is so formed that after thus moving each plunger outwardly and deflecting its spring 5 from the normal position, it suddenly releases said plunger, permitting the spring to oscillate or vibrate in a vertical 65 plane so as to cause the rapid reciprocation of each of the hammers 3 in a line radial to the spindle 4. On the table 1 are placed a quantity of small balls 11 preferably made of hardened steel. 70

The rotor shown in Figs. 3 and 4 consists of two actuating vanes 13 and 14 fastened together so as to extend in a diametric line of the table by a rigid strap 16 connected at its middle to a bearing member 15 rotatably engaging the spindle 4;—the proportions of the parts being such that the vanes are held just clear of the top of the table so that the rotor as a whole may freely turn on the spindle as an axis. A pulley or 80 equivalent structure 20 is mounted on the rotor to permit of the utilization of its rotary movement. Each of the vanes 13 and 14 consists of two angular members 17 preferably of a hardened steel, connected by a yoke 85 18 to one end of the strap 16 so that each vane in effect consists of a straight rigid bar provided with a wedge-shaped passage or opening 19; the relatively narrow outlets to said passages being on opposite sides of a 90 vertical plane passing through the vanes and of a width larger than the diameter of the balls 11.

The rotatable member shown in Figs. 5 and 6 likewise consists of a bearing member 95 15, a strap 16 connected thereto, and two vanes 13^a and 14^a respectively connected to the ends of said strap so as to extend in a diametrical plane of the table. These vanes however each consists of a continuous bar 100 without openings or passages therethrough.

To operate the device the pulley 9 is turned by any suitable means, such as a belt, from a source of power and as the cam 8 moves past the circle of plungers 7, it successively 105 engages them, first so deflecting each spring and its attached hammer 3 that the latter is moved away from the center of the table and thereafter releasing each plunger, with the result that the hammer is given a rapid 110 vibratory movement which is maintained until its plunger 7 is again engaged by the

cam 3. As a consequence all of the hammers are maintained in continuous, rapid vibration toward and from the center of the table.

5 If now the balls 11 are put in motion so that they ultimately strike or are engaged by the hammers 3, they will have further motion imparted to them and all of them will be kept in a state of continuous agitation—each ball travelling in a straight line over the surface of the table until it strikes and rebounds from another ball or from a moving hammer. The surface of the table is thus continually being traversed by the balls moving at a high velocity, and the random nature of the motion insures that approximately every straight line that can be drawn upon the surface of the table will be traversed, in each direction by one 10 or more balls, if the machine is operated for a sufficiently long time. If now the rotor illustrated in Figs. 5 and 6 be placed upon the pivot 4 as shown, each of its vanes in a relatively short time will receive a great 15

20 number of blows from the moving balls. The number of blows per second is the same on each side of each of the vanes 13^a and 14^a as is also the average intensity of the blows and therefore the only motion imparted to the rotor is a slight oscillation resulting from the individual blows struck by the balls upon its vanes.

25 If on the other hand the rotary member illustrated in Figs. 3 and 4 be substituted for that previously mounted on the pivot 4, it immediately begins to rotate in a counter clockwise direction upon the pivot 4 and by means of a belt on the pulley 20 may be caused to perform useful work. This motion is due to the fact that while the same 30 number of balls strike on each side of each vane, some of them entering the passages 19 from the larger ends thereof, strike the sloping sides of the members 17 and pass completely through said passages. Such balls retain most of their original motion and direction and consequently exert upon the movable element a force of less intensity than they would if they did not pass through 35 the openings 19.

40 On the other hand the balls glancing from the external sloping surfaces of the angle members 17 do not pass through the openings 19 but strike upon and rebound from the radial portions of the vanes. Consequently the average force of the blows on 45 that side of each vane from which the passage 19 tapers is less than that on the opposite side of such vane, and there is consequently an unbalanced total force acting on each of the vanes tending to move it in the direction noted.

50 The above described action constitutes a mechanical analogy in one plane of the action of air molecules on two different types

55 of thin membranes, the small balls representing the molecules in random motion as is assumed to be the case by the kinetic theory of gases. The rotor illustrated in Figs. 5 and 6 represents an ordinary membrane mounted in the air so that the pressure resulting from the impacts of the air molecules is equal on both of its faces or sides. The vanes 13 and 14 of the rotary member 60 illustrated in Figs. 3 and 4 represent a membrane perforated with small funnel shaped holes and the above described action conclusively demonstrates that a thin membrane perforated with funnel shaped holes and immersed in a gas, tends to move and 65 could be used to impart useful rotary motion to a shaft or other mechanical device, provided that such holes were sufficient in number for the device to exert an appreciable total effect. Obviously many millions of 70 holes would be necessary to each square inch of surface in view of the relatively small mass of the individual gas molecules.

75 I claim:

80 1. The combination of a series of relatively small bodies freely movable in a single plane; means for maintaining said bodies in random motion; and means for converting the random motion of said bodies into directed motion.

85 2. The combination of a series of relatively small bodies; means for maintaining said bodies in random motion; and a device for converting said random motion into directed useful motion.

90 3. The combination of a series of relatively small bodies; means for maintaining said bodies in random motion; and a device for converting said random motion into directed useful motion consisting of a rotatable structure mounted in the field of movement of the small bodies, said structure having openings permitting passage through it of greater numbers of said bodies in one direction than pass in an opposite direction.

95 4. The combination of a supporting structure having a flat horizontal surface; a series of balls on said surface; means for maintaining said balls in random movement over the surface within predetermined limits; and a rotatably mounted device for converting the random movement of the balls into useful directed movement.

100 5. The combination of a supporting structure having a flat horizontal surface; a series of balls mounted on said surface; means for maintaining said balls in random movement over the surface within predetermined limits; and a rotatably mounted device for converting the random movement of the balls into useful directed movement, consisting of a rotatably supported vane having through it tapering openings permitting passage of greater numbers of said balls from one side than from the other.

105 110 115 120 125 130

6. The combination of a supporting table; a series of balls thereon; a series of vibratory hammers for maintaining the balls in random movement within predetermined limits; means for operating the hammers; and a device for converting the random movement of the balls into useful directed movement.

7. The combination of a supporting table having a substantially flat surface; a series of vibratory hammers surrounding said table; means for actuating the hammers; a series of elements on the table maintained in random movement by the action of the hammers; and means for converting the random movement of said bodies into useful directed movement.

8. The combination of a supporting table having a substantially flat surface; a series of vibratory hammers surrounding said table; means for actuating the hammers; a series of elements on the table maintained in random movement by the action of the

hammers; and means for converting the random movement of said bodies into useful directed movement consisting of a rotatably mounted vane having through it funnel shaped passages extending in lines substantially parallel with the surface of the table and permitting passage of larger numbers of said bodies from their wider ends through the vane than in the opposite direction.

9. The method which consists in subjecting two faces of a structure having substantially flat portions through which extend tapering passages, to the action of a series of small bodies in random motion, to cause a greater number of said bodies to pass in one direction through each passage than passes in an opposite direction, and thereby exert an unbalanced pressure on the structure; and utilizing such pressure to perform useful work.

HAVILAND H. PLATT.
